UNITED STATES PATENT OFFICE.

JAMES E. DAVIS, OF SALEM, OHIO.

RECEPTACLE-WASHING MACHINE.

1,281,302.

Specification of Letters Patent. Patented Oct. 15, 1918.

Application filed January 2, 1918. Serial No. 210,008.

To all whom it may concern:

Be it known that I, JAMES E. DAVIS, a citizen of the United States, residing at Salem, in the county of Columbiana and State of Ohio, have invented certain new and useful Improvements in Receptacle-Washing Machines; and I do declare the following to be a full, clear, and exact description of the invention, such as will enable others skilled in the art to which it appertains to make and use the same.

My invention has for its principal object to provide a simple and inexpensive machine for thoroughly washing cuspidors and other receptacles without touching them with the hands.

In carrying out the above object, a further object is to mount the receptacle support so that it may be tilted to discharge the washing liquid from the receptacle after washing of the latter; and this tilting requires means for tightly holding the receptacle in place, a further object of my invention therefore being to supply this need.

Yet another object is to so mount the cleaning element as to permit it to rotate either concentrically or eccentrically, for thoroughly washing both the bottom and the sides of the receptacle, and in this connection a still further object is to provide for relative adjustment of the receptacle support and the cleaning element so that both the upper and lower portions of the receptacle may be thoroughly washed.

With the foregoing general objects in view, the invention resides in the novel features of construction and unique combinations of parts to be hereinafter fully described and claimed, the descriptive matter being supplemented by the accompanying drawings which form a part of this specification and in which:

Figure 1 is a side elevation of the improved machine;

Fig. 2 is an additional elevation of the side of the machine shown at the left of Fig. 1;

Fig. 3 is a vertical section on the plane of the line 3—3 of Fig. 2;

Fig. 4 is a view similar to Fig. 3 but indicating the cleaning element mounted for rotation eccentrically and also illustrating the receptacle support in an inverted position;

Fig. 5 is a horizontal section on the plane indicated by the line 5—5 of Fig. 3;

Fig. 6 is a perspective view of the receptacle support; and,

Fig. 7 is a perspective view showing more particularly the motion limiting and locking means for the lever which is employed for normally holding the receptacle support or platform against tilting.

In the drawings above briefly described, the numeral 1 designates a suitable type of supporting frame whose structural details form no part of the present invention and need not therefore be described. It is essential, however, that this frame be provided with a pair of vertically disposed guides 2 which may well be formed of vertical bars 70 having slots 3. The guides 2 are located on opposite sides of the frame and a horizontal platform 4 is positioned between said guides for supporting the receptacle R to be washed. Platform 4 is provided with oppositely extending trunnions 5 and 6 which are received in the slots 3, both of said trunnions having rectangular heads 7 which prevent endwise shifting of the platform by abutting the outer sides of the guide bars 2.

The outer end of trunnion 6 is provided with a hand crank or the like 8 for tilting the platform 4 when required, but in order to normally hold this platform against such tilting, the head 7 of the other trunnion is received in a slot 9 formed in a preferably vertical hand lever 10, said lever being fulcrumed at its lower end to the frame as shown at 11. When lever 10 is in the position of Figs. 1, 2, 3, 5 and 7, the platform is held against tilting, but when said lever is shifted outwardly to the position indicated in Fig. 4, said platform may turn as required. To limit the outward movement of lever 10 and to hold this lever in operative

position, a link or rod 12 is pivoted thereto and slides through one or more eyes 13 on the frame 1, the end of said rod opposite the lever being bent upon itself at 14 to provide a hook for engagement with one of the eyes 100 to limit the outward movement of the lever, said rod being bent laterally as shown at 15 after forming the hook, to provide an arm for detachable engagement with a pin or any suitable keeper 16 rising from a portion of the frame. This arrangement is most clearly shown in Fig. 7 and from this figure it will be obvious that when the arm 15 and the keeper 16 are in operative relation, the lever 10 will be held in vertical position to pre-

vent tilting of the platform 4. When, however the arm 15 is released from pin 16, the lever may swing outwardly until the hook 14 strikes one of the eyes 13.

5 Another feature by preference associated with the lever 10 and acting to hold the latter in a truly vertical position, is a lug 17 extending outwardly from the frame 1 and receivable in an opening 18 in said lever.

10 The cleaning element 19 is positioned above the platform 4 and is preferably in the form of a common type of mop, although any other preferred device could well be employed. The platform 4 is movable upwardly toward the mop to position the latter in the receptacle R for washing purposes, and is movable away from said mop to permit tilting of the receptacle to discharge the washing liquid therefrom. This upward and 15 downward adjustment of the platform is permitted by reception of the trunnions 5

20 d 6 in the slots 3, and for holding said platform upwardly in operative relation with the mop, removable pins 20 preferably extend across said slots beneath said trunnions 25 as will be clear from Fig. 3. These pins are receivable in vertically spaced openings 20' in the bars 2 and when the platform is held in completely raised position, its bottom may 30 be washed, while lowering of said platform to a suitable extent and the shifting of the top 19 to an eccentric position yet to be described, will permit washing of the upper edge of the receptacle wall, the lower portion 35 of such wall being cleaned by shifting the mop to said eccentric position without lowering the platform. When the platform is lowered to the maximum as shown in Fig. 4, the lever 10 may be released and said platform 40 then tilted by means of the crank 8 so that the washing liquid will be discharged from the receptacle previously operated upon by the mop 19.

The mop 19 is provided with an upstanding shank 21 preferably forked at its upper end and pivoted at 22 to the lower end of the vertical drive shaft 23. A removable pin 24 is provided for holding the shank 21 either in line with shaft 23 to cause concentric rotation of the mop, or for holding said shank and shaft in angular relation as depicted in Fig. 4, thus causing eccentric rotation of the mop for washing the sides of the cuspidor or the like. For driving shaft 50 23 bevel gears 25, a shaft 26, and a hand crank 27 are preferably employed, although any other preferred operating means could well be utilized.

For the purpose of holding the receptacle 60 upon the platform 4, numerous arrangements could of course be employed, but for illustrative purposes I have shown the following: A pair of posts 28 and 29 rise from opposite ends of the platform 4 to receive 65 the receptacle therebetween, the post 28 be-

ing formed with a pair of openings 30 spaced apart vertically while post 29 is formed with a vertical notch 31 having keeper teeth 32 along its opposite sides. A pair of outwardly bowed rods or wires 34 70 are adapted to have one end passed through either opening 30 as will be clear from Fig. 5, the intermediate portions of said rods embracing the receptacle, while the other ends thereof are received in the notch 31 and engage with the keeper teeth 32. Other rods 35 are provided for holding the receptacle in contact with the platform, said rods passing over said receptacle and having one end received in openings 36 along the edges of the 80 post 28, the other ends of said rods being engaged with keepers formed by lateral lugs 37 which extend from the upper end of post 29.

In addition to the holding means above 85 described, a pair of smaller posts 38 preferably rise from the platform and support the ends of one or more wire rods 39, said rods limiting the lateral movement of the receptacle when the latter is being placed upon 90 the platform. Also, this platform may be provided with a plurality of openings 40 disposed at suitable locations for receiving appropriate pegs or the like, such pegs being instrumental in holding differently 95 shaped and sized cuspidors and the like upon the platform 4.

In operation, the cuspidor or other receptacle to be cleaned is secured upon the platform 4 while the latter is in lowered position, said platform being then raised to position the mop 19 in said receptacle and being supported in such position by the pins or the like 20. The lever 10 is swung inwardly and locked by the rod 12 to prevent 100 tilting of the platform and the crank 27 is then rotated. It is of course understood that either before or after placing the receptacle upon the platform, a suitable quantity of washing liquid is placed in said receptacle. With the parts positioned as shown 110 in Fig. 3, rotation of the mop by the crank 27 and the other driving means, will thoroughly clean the bottom of the receptacle, and when this is done, the mop may 115 be swung to the eccentric position shown in Fig. 4 so that the side of the receptacle may be cleaned around its lower edge portion. This having been done, the platform may be lowered and thus the upper portion of the 120 side wall may be cleaned. When the cleaning operation is completed, the lever 10 is swung outwardly and the platform 4 is inverted by means of the crank 8 to discharge the liquid from the cleaned receptacle (see 125 Fig. 4). This having been done, the platform is returned to normal position, the receptacle is removed and another secured in place to be cleaned.

The machine is rather simple and there- 130

fore may be manufactured at small cost, yet it will be highly efficient and durable. Since probably the best results are obtained from the several details shown and described, these details are preferably employed, but within the scope of the invention as claimed, numerous minor changes may well be made.

I claim—

- 10 1. A receptacle washer comprising a rotary cleaning element, a platform for the receptacle movable upwardly toward said cleaning element and downwardly therefrom, said platform being mounted for tilting, whereby to discharge the washing liquid from the receptacle, means for securing a receptacle upon said platform, and means for normally holding said platform against tilting.
- 15 2. A receptacle washer comprising a rotary cleaning element, a platform for the receptacle movable upwardly toward said cleaning element and downwardly therefrom, said platform having trunnions, vertical guides in which said trunnions are received, means for holding the platform in elevated position, means for normally holding said platform against tilting but for permitting tilting thereof to discharge the washing liquid from the receptacle, and means for holding the receptacle upon said platform.
- 20 3. A structure as specified in claim 2, said tilting preventing means comprising a head on one of said trunnions, and a releasable latch member held against rotation and normally engaging said head.
- 25 4. A structure as specified in claim 2, said tilting preventing means comprising a head on one of said trunnions, a lever having an opening non-rotatably receiving said head,

and means for holding said lever in operative position.

5. A structure as specified in claim 2, said tilting preventing means including a hand lever, a link for limiting the swinging of said lever, an arm extending laterally from said link, and a keeper coacting with said arm to hold the lever in operative position.

6. In a receptacle washer having a receptacle support, a pair of fixed posts rising from said support and adapted to receive the receptacle therebetween, and receptacle holding rods extending between said posts, one post having receiving means for one end of said rods and the other post having keepers for detachable engagement with the other ends of said rods.

7. In a receptacle washer having a receptacle support, a pair of fixed posts rising from said support and adapted to receive the receptacle therebetween, and receptacle holding rods extending between said posts, one post having receiving means for one end of said rods, the other post having a vertical rod receiving notch opening through its upper end, the sides of said notch having additional notches for engagement with said rods.

8. A structure as specified in claim 7, together with additional receptacle holding rods extending between the two posts, said notched post having lateral lugs forming keepers for said additional rods.

In testimony whereof I have hereunto set my hand in the presence of two subscribing witnesses.

JAMES E. DAVIS.
